UNITED STATES PATENT OFFICE.

BERNT STENSRUD, OF PHILADELPHIA, PENNSYLVANIA, ASSIGNOR TO LUDVIK M. PETTERSON, OF PHILADELPHIA, PENNSYLVANIA.

BRUSH.

1,314,441.

Specification of Letters Patent. Patented Aug. 26, 1919.

Application filed May 7, 1918. Serial No. 233,114.

To all whom it may concern:

Be it known that I, BERNT STENSRUD, a subject of the King of Norway, residing at Philadelphia, in the county of Philadelphia and State of Pennsylvania, have invented 5 new and useful Improvements in Brushes, of which the following is a specification.

An object of the invention is to provide a brush for cleaning purposes.

10 The invention comprehends among other features, the provision of a brush which may be adapted to various purposes, but which is particularly adapted for use in cleaning automobiles, as to the body, wheels, and 15 other parts thereof, and to this end the brush is of a fountain nature, whereby the bristle part thereof can be saturated with water, or some other cleaning fluid, during the brushing operation to loosen any foreign elements, 20 or the brush may be used in the nature of a nozzle to direct a steady strong stream of water or other cleaning fluid, against the part to be cleaned in order to loosen the foreign elements, so that the brush will 25 readily brush them away, or remove the foreign elements after the fluid has loosened the same.

In the further disclosure of the invention, reference is to be had to the accompanying 30 drawing, constituting a part of this specification, in which similar characters of reference denote corresponding parts in all the views, and in which—

Figure 1 is a vertical longitudinal sectional 35 view taken through the brush.

Fig. 2 is a sectional view taken on the line 2—2 in Fig. 1.

Fig. 3 is a fragmentary face view showing the operating parts, and

40 Fig. 4 is a fragmentary enlarged vertical sectional view through a modified form of nozzle.

Referring more particularly to the views, the numeral 10 indicates a tubular body or 45 stem, having a suitable threaded portion 11 for a coupling 12 of a hose 13. The body or stem 10 is enlarged at 14 to provide a bristle portion in which a series of bristles 15 are disposed, said enlarged body portion 14 having a series of ducts 16 from a central channel or canal 17 extending entirely through the body, whereby to supply water to the bristles 50

15. At the free end of the brush body and disposed in the canal or conduit 17 is a suitable 55 spring-actuated valve 18 forming a part of

a nozzle 19 of the brush body, and which is formed by cutting an enlarged opening 20 into the end of the brush body to communicate with the canal 17. The valve 18 is operated by a cord or wire 20^a, which passing 60 longitudinally through the canal toward the inner end of the brush body, extends exteriorly to connect with an operating element 21 in the nature of a sliding collar, and which carries a screw 22, operating in a 65 slot 23 in the tubular body 10, so as to limit the forward and backward movement of the collar. The cord or wire 20^a passes through a tube 24 where it extends from the interior of the body to the exterior thereof, and the 70 tube is provided with a suitable packing 25 and jam nut 26. It will be clear that when the collar is slid downwardly or rearwardly on the tubular stem, the valve 18 will be 75 opened, and when the collar is released the 80 spring action of the valve will close the same.

The central channel or canal 17 is in fact formed by a tubular stem 27 which passes 85 entirely through the tubular body 10, and around which the body 10 can be turned. It will be seen that the ducts 16 normally register with ducts 16^a in the stem 27, and that when the body 10 is turned around the stem, the ducts 16 and 16^a will be moved 90 out of register, thus closing the ducts 16 so that water or fluid passing through the hose can be directed out through the nozzle end, instead of coming out through the bristles of the brush. This turning movement is limited by having a screw 28 extending through 95 an opening 29 in the tubular body and connected to the inner stem 27, said opening 29 being more in the nature of a slot, as shown in Fig. 2, so that the turning of the tubular body 10 on the stem 27 will be limited in either direction.

In Fig. 4 I disclose a modified form of 100 my invention, and in which the outer end of the tubular body 10^a is formed with a flared head 30 and a nozzle element 31 is threaded into the head, the valve being of course indicated by the numeral 18. With this arrangement, different forms of nozzle elements 31, of different diameters and sizes, 105 can be employed to form a spray or stream, as desired.

In the use of the invention, it will be clear 110 that when the device is in the position shown in Fig. 1, the fluid admitted to the stem 27

will be ejected through the registering ducts 16 and 16^a to saturate the bristles, so as to facilitate the cleaning action of the bristles. Now when it is desired to direct a stream of water on the body to be cleaned, the tubular body 10 is rotated on the stem 27 to move the ducts 16 and 16^a out of registration, thus closing the ducts 16, and then by sliding the collar 21 on the tubular body, the valve 18 will be moved into open position, so that the water or fluid passing into the brush will be squirted out through the nozzle end in a steady stream or spray.

It is of course understood that the relative movement of the body 10 and stem 27 to cut off the duct 16 is a comparatively small one, and that the flexibility of the cord 20^a will permit this movement without interfering in anyway with the valve 18.

20 I claim:

1. A brush comprising a tubular body, a conduit arranged within the body and in open communication with the source of supply, said body being formed with ducts, and the conduit being formed with openings adapted to register with said ducts in cer-

tain position of the conduit and body, a discharge nozzle arranged in one end of the conduit and opening through an end of the body, a valve operable in the conduit and adapted to close said discharge nozzle, and means mounted on the body and connected with said valve whereby the valve may be operated at will.

2. A brush comprising a body provided with bristles and having discharge ports formed therein, a conduit rotatably mounted in the body and formed with openings adapted to register with said conduit, a nozzle mounted in the end of the conduit and opening through the end of the body, a valve longitudinally movable in the conduit and adapted to control the opening to said nozzle, an operating member slidably mounted on the body, and a flexible connection between said operating member and valve, whereby the valve may be opened or closed in either position of the conduit relative to the body.

In testimony whereof I affix my signature.

BERNT STENSRUD.
